UNITED STATES PATENT OFFICE

141,419

DESIGN FOR A PHOTOGRAPHIC CAMERA OR THE LIKE

Jacques Bolsey, New York, N. Y.

Application August 25, 1943, Serial No. 110,994

Term of patent 14 years

(Cl. D61—1)

To all whom it may concern:

Be it known that I, Jacques Bolsey, a former citizen of Russia having first papers of United States citizenship, residing in New York, county of New York and State of New York, have invented a new, original, and ornamental Design for Photographic Cameras or the like, of which the following is a specification, reference being had to the accompanying drawing forming part thereof in which:

Figure 1 is a top view of a photographic camera showing my new design,

Figure 2 is a bottom view,

Figure 3 is a side view,
Figure 4 is a rear view,
Figure 5 is a front view, and

Figure 6 is a bottom view with the side plate removed of the camera shown in Figure 1.

The dominant features of my design reside in the portions shown in full lines.

I claim:

The ornamental design for a photographic camera or the like, as shown and described.

JACQUES BOLSEY.
